DISPENSING MACHINE

Carl L. Grau, Ottawa, Ill.

Application November 16, 1938, Serial No. 240,780

7 Claims. (Cl. 312—36)

This invention relates to coin controlled dispensing machines for dispensing bottle goods and the like.

The principal object of this invention is to provide a simple and efficient bottle dispensing machine which is easily operated to dispense a cooled bottle of beverage upon the insertion of a coin therein.

Another object is to provide a compact and efficient coin controlled bottle dispensing machine which is practically foolproof in that the operation thereof is simple and which can be operated by anyone in an obvious manner.

A further object is to provide such a machine that is theftproof in that it is impossible to operate the device without first inserting a coin and from which bottles cannot be obtained without operating it in the intended manner.

Still further objects will be apparent from the following description and from the drawings wherein a selected embodiment of the invention is illustrated and in which

Fig. 1 is a side elevation showing the door panel opened and partly broken away;

Fig. 2 is a sectional view taken through the center of the machine from side to side thereof;

Fig. 3 is a front elevation;

Fig. 4 is a side elevation of a portion of the machine taken from the opposite side from that shown in Fig. 1 and showing the side panel removed;

Fig. 5 is a detail view of a portion of the mechanism shown in Fig. 4 showing another position thereof;

Fig. 6 is a sectional view of the bottle discharge mechanism;

Fig. 7 is a sectional view similar to Fig. 6 showing the parts in another position;

Fig. 8 is a detail elevational view of part of the mechanism shown in Figs. 7 and 8 showing the parts in still another position;

Fig. 9 is a detail front elevation of the mechanism shown in Fig. 8;

Fig. 10 is a plan view in section showing the bottle discharging mechanism;

Fig. 11 is an enlarged detail plan view in section of the bottle carrying drum operating and locking means;

Fig. 12 is a sectional view taken on the line 12—12 in Fig. 11; and

Fig. 13 is a sectional view taken on the line 13—13 in Fig. 11.

Referring to the drawings, the coin controlled bottle vending machine embodies a cabinet 14 provided with suitable insulation to prevent, as well as is practically possible, heat passing thereto. A suitable mechanical refrigerating device 15 is provided in the base of the cabinet and is connected to a refrigerating coil 16 in the bottom of the bottle cooling compartment 17 arranged above the refrigerating device 15. The cabinet is adapted to be filled with water to the line 18,

Fig. 1, so that the bottles will be immersed in the cooled water just prior to dispensing of the bottles from the machine. The coil 16 is completely immersed in the water. A suitable passage 19, in the present instance arranged in a sinuous manner, is provided in the top of the machine to receive and retain the bottles therein and which bottles are fed by gravity to the dispensing mechanism at the base of the bottle cooling compartment. It should be understood that any suitable arrangement of storage passage or passages may be used. A drum 20 is pivotally mounted upon an axle 21 journaled in the cabinet walls at opposite sides thereof. The drum 20 is provided on its periphery with corrugations or serrations adapted to fit the contour of the body of the bottles 22. The weight of the bottles in the storage passage is sufficient to normally rotate the drum in a counterclockwise direction, Fig. 1, but undesired rotation is controlled by the stop finger 23, Figs. 6, 7 and 8. The stop finger is normally adapted to abut the side of one of the corrugations on the periphery of the drum as in Fig. 7. A suitable coin inserted in the slot 24, Fig. 10, slides downwardly through the slug detecting device 25 of any suitable construction and passes from the coin chute 26 into the detent 27, Fig. 4, in a suitable controlling arm 28 pivoted at 29. The part 30 of the arm 28 is adapted to abut the stop 31 when no coin is deposited in the detent 27. Thus the parts controlled by the arm 28 will not operate and, as will be described, a bottle will not be dispensed from the machine. The stop 31 is pivoted at 32 so that the rounded surface of the coin in the detent 27 will, however, raise the free end of the stop 31 against the action of the spring 33 to remove the stop 31 from position to engage the part 30, and the arm 28 will then be free to rotate about its pivot to the position shown in Fig. 5, raising the leg 34 integral with the arm 28 and also raising the link 36. The link 36 raises the arm 37 of a lever 38 pivoted on one end of the rod 39, lowering the arm 40, slotted at 40', of the lever 38. The rod 39 is journaled in the inner side walls 41 and 42 of the cabinet and, as will be seen in Fig. 10, extends from side to side of the machine within the cabinet 14. The rod 39 has fixed to its other end a lever 43. The lever 43 has an arm 44 thereon which, like the arm 40 of the lever 38, is slotted at 44' to receive the rod 45 mounted in the slots 46 and 47 in the inner walls 41 and 42 respectively for vertical movement therein. The lever 43 is also provided with an arm 48. A rod 49 is pivotally secured to the free end of the arm 48 and extends outwardly through the front wall of the cabinet 14 where it is provided with a suitable handle 50 on its external end.

After a coin has been inserted in the slot 24 the operator then grasps the handle 50, pulling it outwardly, which pivots the lever 43 and ro-

tates the rod 39 and swings the arms 40 and 44, lowering the rod 45 in the slots 46 and 47. In the same motion the rod 36 is raised, rotating the arm 28. As has been explained, this rotation is prevented, if no coin is in the detent, by abutment of the part 30 against the stop 31. A suitable spring 51, Fig. 4, is provided to assist in returning the rod 45 to normal raised position in the slots 46 and 47. A link 52 has a slot in its upper end which engages the rod 45 and after lost motion provided by the slot in the link 52, the rod 45 will lower the link, rotating a ratchet device 53 about the axle 21 on which it is loosely mounted. The ratchet device is illustrated in detail in Fig. 12. If the inherent friction of the parts is too great, or when the passage 19 becomes empty of bottles and there are only a few bottles arranged in the corrugations or serrations in the drum 20, the ratchet device 53 insures proper rotation of the drum. The ratchet device comprises a housing 54 to which the link 52 is secured. A spring pressed pawl 55 is mounted in the housing and is adapted to engage the teeth 56 suitably provided on one end wall of the drum 20. Another pawl 57, arranged in a housing 58, also engages the teeth 56 to prevent backward rotation of the drum 20.

A bottle raising mechanism, generally indicated by 59, Figs. 6, 7, 8 and 9, is mounted on the rod 45. The mechanism 59 comprises a pair of rods 60 extending horizontally from the rod 45 and interconnected at their outer ends by a rod 61, Fig. 9. A vertical frame work 62 is suspended from the rod 45 at each end of the mechanism with substantially horizontal pieces 63 and 64. The piece 63 is adapted to engage the neck 65 of the bottle at the topmost portion of the drum, and the piece 64 is adapted to engage the body of the bottle. It will be noted that the piece 64 is inclined slightly so that when the bottle is raised to the uppermost position shown in Fig. 6 the body of the bottle will tend to roll off of the piece 64 while the neck is retained on the piece 63 thus insuring that the bottom of the bottle will be discharged through the chute 66. This is illustrated in Fig. 10. It will also be noted that the contour of the chute is such that it assists in insuring that the bottom of the bottle is discharged through the chute first. A spring pressed pawl 67 is secured on the piece 64 of the frame work 62. In the downward movement of the frame 62 at the time the handle 50 is pulled outwardly, the pawl engages the lever 68 connected with the stop finger 23, thus raising the stop finger 23 into the position shown in Fig. 8 to release the stop finger from engagement with the periphery of the drum 20, thus permitting the drum to rotate. The lever 68 has connected thereto a link 69 which link is also secured to the lever 70 pivoted at 71. Another link 72 is secured to the other end of the lever 70 at one end and to the stop finger 23 at the other end and it will thus be seen that downward movement of the lever 68 causes upward movement of the stop finger 23. The parts are arranged so that shortly after the drum starts to rotate, the pawl 67 rides past the end of the lever 68 and the spring 73 causes the lever to pivot and the stop finger to lower so that the stop finger will engage the side of the next corrugation on the frame 62, stopping the rotation of the drum. Upward movement of the frame 62 caused by pushing the handle 50 inwardly brings the pawl 67 into engagement with the bottom of the lever 68. But the pawl is mounted

to ride past the lever 68 without operative engagement therewith. The chute 66 is provided with a hood 74 which directs the bottle downwardly from the chute to the receiver 75. The receiver 75 is preferably lined with a rubber or like material to cushion the fall of the bottle. Likewise, a metal leaf spring may be inserted in the hood 74 if desired so that enough friction will be exerted against the falling bottle to reduce its speed. The bottom of the receiver 75 and the outer side thereof are tilted as shown in Figs. 6 and 7 so that when the bottle comes to rest therein after striking the rubber lining the neck of the bottle will be tilted outwardly for easy removal of the bottle from the receiver.

In operation the customer first places a coin in the slot 24 which passes down the coin chute 26 into the detent 27 in the arm 28 where it comes to rest. The operator then grasps the handle 50 pulling it outwardly, thus lowering the arm 44, rotating the shaft 39 and lowering the arm 40. This action immediately raises the arm 31, link 36 and leg 34. The arm 28 lowers and the coin in the detent 27 raises the stop 31 against the action of the spring 33 to the position shown in Fig. 5. After the coin passes the pivot 32 for the stop 31, the coin drops out of the detent into a suitable receptacle therebelow. Lowering of the arms 40 and 44 first lowers the frame 62 from the position of Fig. 6 to the position of Fig. 7. During this operation the pawl 67 engages the arm 68, raising the stop finger 23, permitting the weight of the bottles in the passage 19 to rotate the drum 20 slightly. If there are no bottles in the passage 19 and there are but a few bottles in the corrugations or serrations in the drum, the ratchet device 53 forces rotation of the drum at the time the rod 45 engages the link 52 at the bottom of the slot 46. This is at the moment the stop finger 23 is raised to the position of Fig. 8. Almost immediately the pawl 67 rides past the end of the lever 68 allowing the stop finger 23 to drop down and be in position to engage the side of the succeeding corrugation, thus insuring the stopping of the drum after it has moved only enough to bring the next corrugation into position. The operator then pushes on the handle 50, reversing the movement of the arm 44, raising the rod 45 with the frame 62, the pieces 63 and 64 of which engage the bottle at the neck and body respectively on the bottom side thereof. Further and continued upward movement of the frame 62 raises the bottle out of the corrugation until the frame is in substantially the position of Fig. 6 whereupon the body end of the bottle rolls off of the frame due to the slight incline of the piece 64 and which bottle movement is insured by the contour of the chute 66. The rod 45 rides up in the slot in the link 52 until it engages the link at its upper end and retracts the ratchet device 53 until the pawl 55 thereof engages the next tooth. During this operation reverse rotation of the drum is prevented by the pawl 57 engaging the teeth 56. The bottle falls through the chute 66 to land in the receiver 75 where it is ready for removal by the purchaser. It will be noted that there are no protuberant levers or handles when the device is not in operation, the handle 50 having been pushed in to deliver the bottle through the chute. A suitable door 76 is provided in one side of the machine to permit removal of coins from the receptacle therefor. The wall 77 on the op-

posite side of the machine is entirely removable to enable stocking of the machine with bottles.

While I have shown and described my invention in a selected embodiment, it is to be understood that it is capable of variation and modification and I therefore do not wish to be limited to the precise details set forth but desire to avail myself of such changes and alterations as fall within the scope of the following claims:

I claim:

1. In a coin controlled bottle vending machine, a casing, storage means in said casing for storing bottles in a horizontal position, a feeding drum for feeding bottles from said storage means to a predetermined discharge position at the top of said drum, means for retaining bottles on said drum during conveyance thereof from said storage means to the discharge position, manually operable means extending through said casing, a lever secured to said manually operable means, a shaft extending transversely of said casing and having said lever secured thereto at one end thereof, another lever secured to said shaft at the other end, means operable by said levers to raise said bottles from said machine, means operable by one of said levers to rotate said drum whereby the bottles fed to said drum will be passed downwardly along one side thereof, around the bottom and up the other side thereof to said predetermined discharge position.

2. In a coin controlled bottle vending machine, a casing, storage means in said casing for storing bottles in a horizontal position, a feeding drum for feeding bottles from said storage means to a predetermined discharge position, manually operable means extending through said casing, a lever secured to said manually operable means, a shaft extending transversely of said casing and having said lever secured thereto at one end thereof, another lever secured to said shaft at the other end, a frame having members thereof engageable with the bottom side of said bottle in discharge position of said drum whereby operation of said manually operable means raises said frame to discharge said bottle in said discharge position from said machine.

3. In a coin controlled bottle vending machine, a casing, storage means in said casing for storing bottles in a horizontal position, a feeding drum for feeding bottles from said storage means to a predetermined discharge position, manually operable means extending through said casing, a lever secured to said manually operable means, a shaft extending transversely of said casing and having said lever secured thereto at one end thereof, another lever secured to said shaft at the other end, and a frame having a pair of members engageable with the bottom side of said bottle in discharge position on said drum, one of said members arranged substantially horizontally and engageable with the neck of said bottle, the other member being inclined and engageable with the body of said bottle, whereby operation of said manually operable means raises said frame to discharge said bottle, body end first, from said machine.

4. In a coin controlled bottle vending machine, a casing, storage means in said casing for storing bottles in a horizontal position, a feeding drum for feeding bottles from said storage means to a predetermined discharge position, manually operable means extending through said casing, a lever secured to said manually operable means, a shaft extending transversely of said casing and having said lever secured thereto at one end

thereof, another lever secured to said shaft at the other end, means operable by said first mentioned lever to insure rotation of said drum to place a bottle in discharge position upon pulling of said manually operable means, and means operable by both of said levers upon pushing of said manually operable means to raise said bottle in discharge position from said drum to discharge said bottle from said machine.

10 5. In a coin controlled bottle vending machine, a casing, storage means in said casing for storing bottles in a horizontal position, a feeding drum for feeding bottles from said storage means to a predetermined discharge position, manually operable means extending through said casing, a lever secured to said manually operable means, a shaft extending transversely of said casing and having said lever secured thereto at one end thereof, another lever secured to said shaft at the other end, means operable by said first mentioned lever to insure rotation of said drum to place a bottle in discharge position upon pulling of said manually operable means, means operable by both of said levers upon pushing of said manually operable means to raise said bottle in discharge position from said drum to discharge said bottle from said machine, and means to prevent the rotation of said drum more than enough to bring a single bottle into said discharge position in each cycle of operation of said machine.

30 6. In a coin controlled bottle vending machine, a casing, storage means in said casing for storing bottles in a horizontal position, a feeding drum for feeding bottles from said storage means to a predetermined discharge position, manually operable means extending through said casing, vertically movable means operatively connected to said manually operable means for raising bottles from said discharge position to discharge said bottles from said machine, a stop finger normally engaged with said drum to prevent bottle feeding rotation thereof, means carried by said vertically movable means adapted to disengage said finger from said drum on downward movement thereof permitting rotation of said drum to place a bottle in discharge position, whereby upon upward movement of said vertically movable means said bottle will be raised from said discharge position and discharged from said machine.

40 7. In a coin controlled bottle vending machine, a casing, storage means in said casing for storing bottles in a horizontal position, a feeding drum for feeding bottles from said storage means to a predetermined discharge position, manually operable means extending through said casing, vertically movable means operatively connected to said manually operable means for raising bottles from said discharge position to discharge said bottles from said machine, a stop finger normally engaged with said drum to prevent bottle feeding rotation thereof, a pawl carried by said vertically movable means, a lever having one end arranged in the path of movement of said pawl and operatively connected to said finger, whereby manual pulling of said manually operable means will lower said vertically movable means effecting disengagement of said finger from said drum permitting bottle feeding rotation thereof to place a bottle in said discharge position and pushing of said manually operable means will raise said vertically movable means to raise said bottle in discharge position therefrom to discharge said bottle from said machine.

CARL L. GRAU.
